US00D344500S

United States Patent [19]

Bruce et al.

[11] Patent Number: Des. 344,500

[45] Date of Patent: ** Feb. 22, 1994

[54] WIRELESS OPTICAL INPUT DEVICE

[75] Inventors: **Richard H. Bruce**, Los Altos; **Scott A. Elrod**, Redwood City; **Thomas P. Moran**, Palo Alto; **Frank G. Halasz**, Santa Cruz; **Malcolm S. Smith**, Palo Alto; **Dallas R. Grove**, Mountain View; **Richard J. Goldstein**, San Francisco, all of Calif.

[73] Assignee: **Xerox Corporation**, Stamford, Conn.

[**] Term: **14 Years**

[21] Appl. No.: **864,903**

[22] Filed: **Apr. 3, 1992**

[52] U.S. Cl. **D14/116**

[58] Field of Search **235/375, 378, 385, 454, 235/462, 472, 486; 354/80-82; 382/58-69; 250/203.1, 216, 566, 568; D14/100, 114, 116; D26/37, 45, 50**

CLAIM

The ornamental design for a wireless optical input device, as shown.

DESCRIPTION

FIG. 1 is frontal perspective view of a wireless optical input device showing our new design;

FIG. 2 is a front view;

FIG. 3 is a right side view;

FIG. 4 is a rear view;

FIG. 5 is a left side view;

FIG. 6 is a top view; and,

FIG. 7 is a bottom view.
